ADJUSTABLE POLE

Gail Hamilton Hines, Lansing, Mich.

Application June 23, 1947, Serial No. 756,517

5 Claims. (Cl. 248—353)

1

This invention relates to the class of poles and more particularly to adjustable combination poles designed for wide range of use from support for clothesline to tent.

The primary object of my invention is to improve the construction and efficiency of poles of the type mentioned by providing simple attachments and adjustments to telescoping tubing.

A further object of my invention is to provide a pole of wide service at a minimum of expense.

Still another object of the invention is to provide a lengthy and adjustable pole which may also be made very compact and portable.

With the above objects and other objects in view, as will appear as the description proceeds, the invention consists of the novel features of construction, combination of elements and arrangement of parts which will be more fully described herein and set forth with particularity in the claims appended hereto.

Reference is had to the accompanying drawings forming a part of this application, in which the like reference characters will indicate corresponding parts throughout the several views, in which—

Figure 1 is a vertical front view of my improved adjustable combination pole,

Figure 2 is a side elevation thereof,

Fig. 3 is a view disclosing an equivalent pawl formation and arrangement.

Fig. 4 is a plan view of the pawl-holding ring, particularly disclosing an equivalent means for locking the pawl on the ring.

Fig. 5 is a sectional view taken on line AA of Fig. 2.

Fig. 6 is a view disclosing an equivalent in the form of a ring-held pawl in combination with a wedge.

Fig. 7 is a fragmentary view showing the bifurcated portion of the upper-end attachment in position for use.

Referring to the drawings in detail, I employ a length of metal tubing 1 and a second length (both preferably annular) 2 having a diameter less than the first so that the tubing 2 will readily slide longitudinally within the tubing 1. A close sliding fit is workable, but I prefer a fairly loose fit in general between the tubing 1 and 2 when I flange a suitable front portion of the lower extremity of the tubing 2, as shown at 16, for use with my pawl arrangement. At the upper front extremity of the tubing 1 I cut out a rectangular section as shown at 10, and in relatively close proximity in direct line below I cut out a hole (either rectangular or circular) as shown at 9 in tubing 1. The cutouts 9 and 10 are made to suitably receive the pawl 3 which is locked to an annular ring 4 after the ring 4 and pawl 3 are assembled upon the tubing 1, the pawl 3 having an opening 6 with a constricted portion

2

a trifle larger than a relatively small section of the ring 4 which has been reduced in thickness by the cutout 5, and whereas the cutout 5 of the annular ring 4 is adequately filled by a punched-out portion of the tubing 1 as shown at 12 after the pawl and ring are thereby ready to be locked together and fixed upon the tubing 1 for limited movement only. The lower, hooked extremity, of the pawl 3 is contained in the cutout 5 of the ring 4 when ring-and-pawl are slid down into operative position from the top of tubing 1, and then with the pawl in assembled position at the front the ring 4 is turned to bring cutout 5 to the rear of tubing 1 for locking as shown at 12. The pawl 3 is seen as being held outward by thumb-and-finger, if a rubber band 39 under tension is used as shown connecting the pawl 3 and the tubing 1.

So now the drawings make it clear that the pawl 3 has a lower projection 8 which rests or hooks on a shoulder (made by the hole or cutout 9) near the upper extremity of the tubing 1, and also it is seen that the pawl 3 has an upper projection designed to be moved in-and-out of a selected one of a series of holes 11 formed in a longitudinal line in the front of the tubing 2, for the purpose of adjusting and fixing the telescoping pole to different lengths as required.

I make an annular flange at the lower extremity 30 of the tubing 1, to make more adequate footing on floor or ground, and when even better footing is required I press a sheet-metal pan or cover 17 over the lower extremity of the tubing 1. And then for still better footing I employ a sizable 35 wooden block or base 18 beneath the pan 17, said base having a length that is several times its width, or as required. The base 18 is removably attached to the tubing 1 by means of springs 22, in pair and fixed at opposite ends of the base 18 by means of a pair of nails 23, the pair of springs 22 being also fixed to a pair of hooks 24 which removably engage with a pair of holes 26 formed in the tubing 1, and suitably disposed on opposite sides of said tubing. A dowel pin 19 is driven 40 into the base 18 and disposed to project vertically from the center of the upper face of the base 18 and to also project through a fitting hole in the center of the pan 17. The dowel pin 19 is made to fit the pan (or hole therein) 17 rather loosely 45 so as to allow for a slight rocking of the pole upon the base 18. The hooks 24 are preferably made from spring wire and may have a thumb-and-finger grip 25 formed in integral connection with each hook. This thumb-and-finger grip 25 serves to facilitate removal of the hooks from the tubing 1 and also facilitates packing the base assembly 50 when detached for compactness in transportation, whereas the hooks 24 are then hooked into suitably disposed staples 20 and 21 driven into the upper face of the wooden base 18.

A dual-form-fitting plug 13, preferably made from hard rubber (or equivalent), quite like a rubber cork, is molded to have a sizable steel pin 14 made integral therewith and to project longitudinally outward from one end only, while at the opposite end of said plug 13 a bifurcated formation provides a groove or notch at 15, so that the plug 13 may have a pressed fit with the upper extremity of the tubing 2 to allow the pin 14 to project longitudinally upward (as for use in supporting a tent), or the pin 14 may be disposed out of service by reversing the plug 13, as shown in Fig. 7 of the drawings, whereas the bifurcated formation and notch 15 come into position for use (as for support in the center of a slack clothesline).

Again referring to Figures 1 and 2 of the drawings, I employ an annular ring 35 made from coiled spring wire so that the inside of said ring 35 has a diameter that is normally less than the outside diameter of the tubing 2, and have a hook 36 integrally formed in connection with said ring 35, and do accordingly expand the ring by virtue of its formation from continuous wire in coils and do then slip the said ring 35 down over the outside of the tubing 2 to be frictionally connected therewith and at such a height or elevation (within limits) as I choose (for use to hold a coat-hanger, as in a tent—or to become a fastener for a clothesline). The hook 36 being formed at either the lower or upper end of the spring wire in coil the other end of the wire in coil in the ring 35 may have formed therewith a detent which is fitting for engagement with a selected hole of the series of holes 11, and for obvious reason the detent 37 may be formed diametrically opposite the hook 36 instead of on the quarter as shown in the drawings, although in any case the ring 35 may be turned upon the tubing 2 to cause the detent 37 to fit a hole 11. Or the end 37 may be formed into a second hook to be engaged with the hook 36 extended and doubled back for fastening in the fashion of a safety-pin, to make a light and most secure fastener in the hook 36. Or in the manufacture of the ring 35, for equal security as a fastener, instead of ending the coil in a detent 37, I may extend the wire of the coil-made ring 35, at the end opposite the hook 36 so as to reach out quite as suggested by the line of dots 38 and have the extended end formed into an eye with tension pressing downward on the hook 36. Whereas an upward projection from the hook 36 would engage with the said eye, obviously to assure a lightweight, secure fastener.

In Fig. 4 of the drawings I suggest the use of a clip 31 to fill the notch or cutout 5 of the steel ring 4, in lieu of employing the punched-out (or pressed-out) portion 12 of the tubing 1, whereas by filling the cutout 5 with the clip 31 the pawl 3 cannot become unhooked from the ring 4, even if the latter should turn or rotate relative to the tubing 1.

In Fig. 3 of the drawings I show the use of a modified form of pawl 32 which is hinged upon the bolt 34 when I employ the bolt 34 in the securing of a clamp 33 properly disposed in connection with the tubing 1.

Referring to Fig. 6 of the drawings, it will be seen that I may employ a wedge 29 in integral connection with a modified form of pawl 28, whereas an annular ring 30 has integral (or otherwise fixed) connection with the pawl 28 and is fitted loosely to slide longitudinally upon the tubing 1 and yet limited in upward sliding move-

ment by a stop 27 formed in the tubing 1 as shown. Obviously the wedge 29, in position as shown, serves to lock the tubing 2 into rigid connection with the tubing 1 when a suitable projection from the pawl 28 is engaged with a hole 11 of the tubing 2 while downward pressure resides in the latter.

Referring to Fig. 5 of the drawings, it will be seen that a lower portion of the punched-out integral part 12 of the tubing 1 is pressed more particularly outward to form as a stop for limiting the downward longitudinal movement of the ring 4 relative to the tubing 1.

Aside from the various modifications shown in the drawings, I have many others in mind with the assumption that I may employ any known equivalent for a particular element or construction which I have shown or described. Still I may offer a few more suggestions from pertinent pictures which I have in mind. Again referring to Fig. 6 of the drawings, I may remove the wedge 29 and allow the ring 30 to become a simple bifurcated integral portion of the pawl 28, whereas rivets with countersunk heads would be employed in opposite sides of the tubing 2 so as to pass through holes in the bifurcated portion of the pawl 28 and so as to fix the pawl 28 to be hinged for adequate limited movement on said rivets. The plug 13 (as shown in Figures 1 and 2 and 7 of the drawings) may be made of metal and threaded to fit suitable threads formed in the tubing 2, or any other known form of connection may be employed to adapt the pin 14 to its intended use. In lieu of the plug 13 (with the notch 15) I may form a suitable notch in the top of the tubing 2 by pressing the front and rear sides at the top suitably inward and downward, and then also a pin connection may be made to snap into this notch formation for ready removal by a thumb-actuated spring. In lieu of holes 11, I may employ notches to fit a chisel-shaped pawl-element, and the tubing 1 and 2 may relate one to the other in a close sliding fit without the use of the flange shown at 16. A small coil spring may go around the tubing 1 and hook into the pawl 3 so as to hold an upper portion of the pawl 3 in the cutout 10 except as thumb-and-finger is employed to pull the pawl 3 outward from a hole 11. The pan 17 need not be used, especially when I employ the base 18 and a fitting depression in the top face of the base 18 in lieu of the dowel pin 19, or even without said depression to fit the lower extremity of the tubing 1. The base 18 may be made of pressed metal with mere holes into which springs 22 would hook in lieu of nails (or screws) 23, and integral ears would be employed in lieu of the staples 20 and 21; and otherwise as I show to be obvious. Moreover, such a special element as the rubber band 39 (or equivalent spring) may be omitted.

Then as clearly seen, I may employ tubing of square or rectangular section, and I may have the lower tubing of rectangular section while the upper tubing (smaller in section and slidably inside the lower) may be of square section and of metal of heavier gage or thickness, to make a construction well adapted to the use of a wide wedge built upon the idea shown in Fig. 6 of the drawings, for the purpose quite obvious in view of other description herewith, and when using a pawl in connection with a wedge for locking telescoping tubing together the upper portion of the lower (larger) tubing may be reinforced with an extra band of metal as required.

to resist pressure of the wedge, and I may employ the flange, as suggested at 16 in Fig. 2, as may be needed when tubing of square section is fitted for use with larger tubing of rectangular section. In fixed connection with the lower portion (below the ring 4) of the pawl 3 I may employ a small flat or wire spring (somewhat as operates in a safety-pin) to bear against the outside periphery of adjacent elevation of tubing for the purpose of normally forcing the pawl element 7 into engagement with a hole 11. Or I may have holes 11 in double series on opposite sides of the tubing 2 so as to employ a simple pin of suitable size pushed through a pair of holes 11 to adjust the length of the pole, in lieu of the pawl 3. And for added length to my improved pole I may employ a length of rod or tubing of smaller section than in tubing 2 so as to be slideable longitudinally within the latter and to be adjusted therewith quite as the tubing 2 is fitted and adjusted with the tubing 1. The plug 13 may be composed of suitable metal which is threaded and accordingly screwed into fitting threads formed on the inside of the tubing 2 and whereas several different attachments like the pin 14 may be alternately screwed into a second threading (either internal or external) of the plug 13, and moreover as I may modify within the scope of my broad idea revealed herewith.

Quite obvious are the common and ordinary uses of my improved pole, and I need suggest only a little further. So I merely add that two of these adjustable poles, with the substantial base 18 attached, may be employed to support a temporary clothesline, whereas loops or eyelets at the ends of the line would be hooked over the pins 14 which are accordingly assembled to extend upward from the plug 13, and whereas also loops of a pair of guy-ropes would likewise hook over the pins 14, and preferably over or above the loops or eyelets of the relatively horizontal line (or clothesline) stretched between the pair of poles. And then a second line may be stretched between a pair of hooks 36, so that towels and washrags or other garments of short extent downward may be hung on one line while the other is adjusted for the hanging of garments of longer extent downward. And then if this double-line assembly is employed (not as a pair of clotheslines) in a play-lot with the pair of poles spaced about sixteen or eighteen feet apart it can form the basic element for playing the game of window ball which is described in detail in my pending patent, Serial No. 624,106, filed October 24, 1945, for Window Ball Play-Device.

From the foregoing description taken in connection with the accompanying drawings, it is thought that a clear and comprehensive understanding of the construction, operation and advantages of my invention may be had, and while I have shown and described the device particularly as embodying a specific structure, I desire that it be understood that such changes may be made in said structure as do not depart from the spirit and scope of the invention as claimed.

Having thus described my invention, what I claim as new, and desire to secure by Letters Patent, is:

1. In a device of the class described, the combination of a length of tubing, a pawl-holder slideable on said tubing, a pawl connected to said tubing by means of the pawl-holder and resilient means connecting the pawl to the ensemble in-

cluding the length of tubing and the pawl-holder, a longitudinally disposed element projecting in sliding connection with the length of tubing, and means in said element to engage with the pawl to make variable length in the resultant pole.

10 2. In a device of the class described, the combination of a length of tubing, a pawl, projection pole means between said tubing and the pawl, a pawl-holder slideable on said tubing and connected to the pawl, resilient means connecting the ensemble including the pawl and pawl-holder to said tubing, a longitudinally disposed element projecting in sliding connection with the 15 length of tubing, and means in said element to engage with the pawl to make variable length in a resultant pole.

20 3. In a device of the class described, the combination of a length of tubing, a pawl, projection pole means between said tubing and the pawl, a pawl-holder slideable on said tubing and having hinge-connection to the pawl, means to limit the 25 length of sliding relation between the pawl-holder and the tubing, resilient means connecting the ensemble including the pawl and pawl-holder to said tubing, a second length of tubing telescoping with the first length of tubing and having means to engage with the pawl with the 30 pawl to make variable length in a resultant pole.

35 4. In a device of the class described, the combination of a length of tubing, a pawl-holder slideable on said tubing, a pawl connected to said tubing by means of the pawl-holder and resilient means connecting the pawl to the ensemble including the length of tubing and the pawl-holder, a longitudinally disposed element projecting in slideable connection with the length of tubing, means in said element to engage with the 40 pawl to make variable length in a resultant pole, a footing element in relative proportion to steady the pole in upright position to facilitate adjustment of the pawl, and resilient means to attach said footing element to a free end of the length of tubing.

45 5. In a device of the class described, the combination of a length of tubing, a pawl, projection pole means between said tubing and the pawl, a pawl-holder slideable on said tubing and having detachable connection to the pawl, a boss on said tubing to limit the length of sliding relation between the pawl-holder and the tubing, resilient means connecting the ensemble including the pawl and pawl-holder to said tubing, a second length of tubing telescoping with the 50 first length of tubing and having means to engage with the pawl to make variable length in a resultant pole, a footing element in relative proportion to steady the pole in upright position to facilitate adjustment of the pawl, and resilient means to attach said footing element to a free end of the telescoping tubing.
